COMPOUND TOOL

William F. Watson, Olean, N. Y.

Application June 14, 1939, Serial No. 279,189

1 Claim. (Cl. 145—50)

This invention relates to compound or combined tools and has for its principal object to provide a wrench handle or the like with a folding screw driver or the like which can be opened out at the rear end of the handle for use as a screw driver or similar device, or which can be folded into closed position into a recess in the handle in which position it will not interfere with the ordinary use and operation of the wrench. 5 A spring is provided which presses against the shank of the auxiliary tool to retain it in either position.

The invention will be more fully understood from the following description in connection with the accompanying drawing, in which:

Fig. 1 is an edge view showing the screw driver in extended position and illustrating the manner in which it may be folded into the handle.

Fig. 2 is a side view.

Fig. 3 is a detail in longitudinal section of part of the wrench handle;

Fig. 4 is a detail in edge view of the screw driver.

In the drawing 6 indicates a wrench head of known construction, joining to a handle 7. This handle is of special construction, having recesses 8 and 9 at opposite sides of a tongue or middle part 10, with an opening 11 connecting the two side recesses. At its rear end the handle has a cross bar or piece 12 at one side of which is a notch 13. The shank of the screw driver 14 is pivoted in the cross opening 11 by a pivot at 15 so that the screw driver may be swung to either closed or open position, as shown in Fig. 1. 30 When swung or folded to closed position it lies within the opening 11 and recess 8 against one side of the tongue 10, in which position it will be substantially flush with the side of the handle and so convenient to operate the wrench in the usual manner, without interference.

40 The shank of the screw driver 14 has a cross notch 16 in which the cross bar 12 fits when the screw driver is swung to open position. In this adjustment the screw driver will project from the wrench handle and in line with the longitudinal axis thereof, in which position it can be manipulated, the wrench head serving as a handle to receive the thrust, and this thrust, it will be noted, is taken largely by the cross bar 12 engaging in the notch 16, instead of solely by the pivot 15.

45 A flat spring 17 is used to retain the screw driver in either position. This spring is seated in the recess 9, at the side of the handle opposite the seat for the screw driver, and the spring is riveted to the tongue 10 by the rivets 18. In either position of the screw driver the spring presses flatly against the side of the shank of the screw driver, and to facilitate the closing

5 movement the inner end of the screw driver is rounded on one side as indicated at 19, the surface 19 wiping over the spring as the screw driver is swung. The pressure of the spring serves to snap the screw driver into either position when it is swung beyond center, and the spring is preferably made of sufficient strength to prevent accidental closure of the screw driver incident to thrust thereon.

10 The screw driver may be provided with a cutting notch and edge at 20 as for scraping insulation from wire; also with a finger notch 21 to receive a finger nail to start the opening movement; also with a short scale of inches 22 along one edge, for measuring purposes.

15 Mounted on the screw driver blade is a half-nut or locking nut 23 having its flat side in alignment with one side of the notch 16 when in inoperative position. After the screw driver is opened the locking nut can be turned to engage the cross bar or piece 12 and thereby lock the screw driver in open position and thus prevent the possibility of the same folding towards closed position during the use of the same.

20 In use it will be seen that the screw driver may be folded to closed position, fitting within the opening 11 and recess 8; or it may be lifted and swung to open position extending in line with the handle, being retained in either position by the pressure of the spring 17. And in either position the spring lies within the surface of the handle, fitting in the opening 11 and recess 9, leaving the handle without objectionable roughness or projections, so that it can be conveniently operated for the use of either the wrench or the 25 screw driver.

30 The invention is not limited to the exact form shown but may be varied within the scope of the following claim.

I claim:

40 A tool handle having two opposite relatively wide sides with an opening extending completely through said handle between said sides and having a tongue projecting from one end of the handle into said opening and a cross bar extending across the handle at the opposite end of said opening, a screwdriver pivoted near one end and at its narrow edges in said opening and adjacent said cross bar and foldable flatwise against one side of said tongue when in folded position and flatwise against said cross bar when in unfolded position, and a flat spring fixed at one end to the opposite side of said tongue and projecting along said opening with its free end bearing against the wide sides of the inner end of the screwdriver to hold the same in either opened or closed position.

45 50 55 WILLIAM F. WATSON.
